(57) **CLAIM**

We claim the ornamental design for a hair clipper, as shown and described.

DESCRIPTION

FIG. 1 is a front perspective view of a first embodiment of the hair clipper showing our new design;
FIG. 2 is a rear perspective view thereof;
FIG. 3 is a bottom view thereof;
FIG. 4 is a top view thereof;
FIG. 5 is a left side view thereof;
FIG. 6 is a right side view thereof;
FIG. 7 is a front view thereof;
FIG. 8 is a rear view thereof;
FIG. 9 is a front perspective view of a second embodiment of the hair clipper showing our new design;
FIG. 10 is a rear perspective view thereof;
FIG. 11 is a bottom view thereof;
FIG. 12 is a top view thereof;
FIG. 13 is a left side view thereof;
FIG. 14 is a right side view thereof;
FIG. 15 is a front view thereof; and,
FIG. 16 is a rear view thereof.

The broken lines in the drawings are for the purpose of illustrating portions of the hair clipper which form no part of the claimed design.
